UNITED STATES PATENT OFFICE.

HENRY M. SHAW, OF CANASTOTA, NEW YORK, ASSIGNOR TO SHERWOOD BROS. MFG. CO. INC., OF CANASTOTA, NEW YORK.

WAGON.

Application filed October 25, 1922. Serial No. 596,702.

To all whom it may concern:

Be it known that HENRY M. SHAW, a citizen of the United States of America, residing at Canastota, in the county of Madison and State of New York, has invented certain new and useful Improvements in Wagons, of which the following is a specification.

This invention relates to wagons and more particularly to the so called child's spring coaster wagon or cart.

The principal object of the invention is to provide a spring assembly for the running gear whereby liability of breakage of the springs or other parts of the running gear is minimized.

Other and further objects and advantages of the invention will be in part obvious and in part described as the specification is proceeded with.

In the accompanying drawings forming part of this description:

Figure 1 is a rear end view of a wagon showing my invention;

Figure 2 is a front end view thereof; and Figure 3 is a side view.

Figure 4 is a detail sectional view of a clip forming part of my invention.

Referring more particularly to the drawings 5, denotes the body of the cart, 6 and 7 the front and rear axles, and 8 and 9 the respective front and rear wheels therefor. The body 5, is supported at its front and rear ends upon the respective axles by means of front and rear bolsters and spring assemblies about to be described.

Mounted on the ends of the front and rear axles on the inside of the wheels 8 and 9, are brackets 10, of substantially S-shape and preferably made of sheet metal straps. These brackets are formed with an intermediate horizontally disposed portion 11, and outwardly and inwardly bent horizontal portions 12 and 13, at their respective upper and lower ends. Apertures 14, are provided in the lower portions of the brackets through which the axles extend, the inwardly bent horizontally disposed lower ends 13, being snugly secured to the axles, as by bolts 15.

Posts 16, pass freely through alined apertures 17 and 18 in the respective upper horizontally disposed portions 12, and intermediate horizontally disposed portions 11, of the brackets 10. Coil compression springs 19 surrounding the posts 16, are interposed be-

tween said horizontal portions 11 and 12, the opposite ends of the springs seating in apertured sockets or seats 20 and 21, loosely mounted on the posts 16. The upper seats or sockets 20, bear against cotter pins 22, 60 extending through the posts 16, which pins limit the upward movement of the said seats or sockets and also the upward throw of the posts, and the lower sockets 21, rest on the horizontal portions 11, of the brackets 10. 65

Front and rear bolsters 23 and 24 respectively are each formed with upwardly bowed intermediate portions 25, and horizontally disposed end portions 26, the latter terminating in vertically disposed portions 27. The 70 horizontally disposed portions 26, which fit snugly beneath and are overlapped by the horizontally disposed intermediate apertured portions 11, of the brackets 10, are apertured as at 27, to receive the lower ends 75 of the posts 16. The vertically disposed portions 27 lie flush with the inner face of the brackets. A bar or strap 28, is pierced at its ends by the lower end of the posts 16, and nuts 29, on the posts clamp the ends of 80 the bar or strap to the said overlapping horizontal portions 11 of the brackets.

The parts so far mentioned and described are common to both front and rear running gear assemblies.

Referring now to the front end of the cart, a preferably U-shaped spacing member or brace 30 is interposed between the bar or strap 28, and the upwardly bowed intermediate portion 25, of the bolster 23, bolts 32, 90 securing the member 30, to the bolster. A downwardly bowed strap or upper bolster member 33 secured at its ends to the body 5, by bolts 34, carries a fifth wheel section 35, which seats upon a corresponding section 95 36, secured to the upwardly bowed portion 25, of the bolster 24. A front brace 37, connected to the body 5, by a bolt 38, is formed with a horizontal portion 39, resting upon the upper face of the downwardly bowed upper front bolster member 33, and with a vertical portion having a horizontally disposed end 40, bearing against the under part or bottom of the body 5. The strap or bar 28, spacing member 30, upwardly bowed bolster 25, fifth wheel sections, downwardly bowed bolster member 33, and the horizontal portions 40, and 41, of the front brace 37, are provided with alined apertures for the reception of the king bolt 42. 110

Forwardly extending tongue straps 52, are connected at their inner ends between the bar 28, and the bolster member 25, by means of bolts 43, and a tongue or handle 44 is pivoted at 45, to the outer or front ends of the straps.

Rear braces 46 are connected to the body at their inner ends as by bolts 47, and rest upon the bar 28, at their outer ends, the said 10 outer ends being provided with apertures 48, receiving the lower ends of the posts 16. Nuts 29, on the ends of the posts clamp the bar 28, the braces 46, and the horizontal portion 26, of the bolster 24, tightly together.

15 Having thus described my invention, what I claim as my invention is:

1. A wagon comprising an axle, brackets supported by the axle, said brackets having horizontal apertured portions, a bolster having an upwardly bowed intermediate portion, and horizontal apertured portions engaging beneath and overlapped by the horizontal apertured portions of said brackets, means for connecting the upwardly bowed 20 portion of the bolster to the body of the wagon, an apertured cross bar above and parallel with the axle, posts extending upwardly through the apertures in said cross bar, bolster and bracket, and means for 25 clamping the cross bar to the bolster, coil 30

compression springs on said posts engaging said brackets at their lower ends, and means on the posts engaged by the upper ends of the springs whereby said springs normally force said posts upwardly through said apertures.

2. A wagon comprising an axle, brackets supported by the axle, said brackets having intermediate horizontal apertured portions and vertical portions extending upwardly 40 therefrom and terminating in upper horizontal apertured portions, a bolster having an upwardly bowed intermediate portion and horizontal apertured end portions, said end portions underlying the intermediate 45 horizontal apertured portions of the brackets, means for connecting the bolster to the body of the wagon, an apertured cross bar, posts extending upwardly through the apertures in said cross bar, bolster and the said 50 intermediate and upper apertured horizontal portions of the brackets, coil compression springs on the posts, means on the upper ends of said posts engaged by the upper ends of said springs, and means on said intermediate horizontal portion engaged by the 55 lower end of said spring.

In testimony whereof I affix my signature.

HENRY M. SHAW.
